Primary Examiner — Ramzi Almatrahi*(74) Attorney, Agent, or Firm* — Westbridge IP LLC(57) **CLAIM**

The ornamental design for a camera lens cap, as shown and described.

DESCRIPTION

FIG. 1 is a front perspective view of a camera lens cap showing our new design;
FIG. 2 is a rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is an enlarged view of portion 9 shown in FIG. 1;
FIG. 10 is an enlarged view of portion 10 shown in FIG. 2;
and,
FIG. 11 is an enlarged view of portion 11 shown in FIG. 5. The dash-dot broken lines in the drawings depict the portions of the camera lens cap which form no part of the claimed design.

The dot-dash broken lines in the drawings depict the boundaries of the partial enlarged views that form no part of the claimed design.
